CLAIM

The ornamental design of a telephone set, as shown and described.

DESCRIPTION

FIG. 1 is a top, front and right side perspective view of a telephone set showing our new design;

FIG. 2 is a front perspective view thereof;

FIG. 3 is a rear perspective view thereof;

FIG. 4 is a right side perspective view thereof;

FIG. 5 is a left side perspective view thereof;

FIG. 6 is a top perspective view thereof; and,

FIG. 7 is a bottom plan view thereof.

The broken line showing throughout the views are for illustrative purposes only and form no part of the claimed design.
